CLAIM

The ornamental design for a kitchen meat shredder, as shown and described.

DESCRIPTION

FIG. 1 is a top plan view of the kitchen meat shredder showing our new design.

FIG. 2 is a front view thereof, the opposite side being a mirror image.

FIG. 3 is a left side view thereof, the opposite side being a mirror image.

FIG. 4 is a bottom plan view thereof.

FIG. 5 is a perspective view thereof.

FIG. 6 is a top plan view of the base of FIG. 1.

FIG. 7 is a front, rear, left and right side view of FIG. 6.

FIG. 8 is a perspective view of FIG. 6.

FIG. 9 is a top plan view of the lid of FIG. 1.

FIG. 10 is a front and rear view of FIG. 9.

FIG. 11 is a left and right side view of FIG. 9.

FIG. 12 is a bottom plan view of FIG. 9; and,

FIG. 13 is a perspective view of FIG. 9.

The base and lid are shown separately for clarity of illustration. The broken lines are for illustrative purposes only and form no part of the claimed design.
